FOUNTAIN PEN

David Wolf, Newton, Mass.
(185 Devonshire St., Boston, Mass.)
Filed May 16, 1966, Ser. No. 531,113
3 Claims. (Cl. 120—46)

The present invention relates to an improved fountain pen.

Certain styles of fountain pens are refilled by dipping the nib into a container of ink to fill an ink sack or reservoir and thereafter withdrawing the pen from the ink. It is then necessary to wipe dry the casing about the nib. This last step is inconvenient, time consuming and messy. It often results in fingers becoming stained with ink.

The present invention is designed to overcome these and other objections to fountain pens of the type described.

In the present invention, the internal components of the pen, except for the tip of the nib, are encased in a two part casing. The upper and preferably shorter part is integrally secured to the internal components of the pen. The lower and preferably longer part forming a hood removably encases the lower internal components of the pen. The bottom of the lower part of the casing has an opening through which the nib projects. These two casing parts are threadably interengaged at adjacent ends. To fill the pen of the present invention, the lower part or hood of the casing is removed, exposing the entire nib and reservoir portions of the pen. Also preferably exposed is the means for filling the pen reservoir. The pen nib is then immersed in the ink well and the reservoir filled. The nib is withdrawn and the lower casing replaced without wiping the nib or the area about it. Since the lower part of the casing covers all but the tip of the nib including that portion of the reservoir which may have been wetted by ink, and since this lower part of the casing is dry on its exterior surface, there is no need to wipe the pen.

These and other objects of the present invention will be more clearly understood when considered in connection with the accompanying drawings in which:

FIG. 1 is an elevational view of a pen embodying my invention;

FIG. 2 is a longitudinal cross-sectional view;

FIG. 3 is an elevational view of a portion of the invention; and

FIGS. 4 and 5 are fragmentary cross-sectional views of modifications of the invention.

A preferred form of the present invention is illustrated in the drawings in which the outer pen casing is formed of an upper part 1 and a lower part 2, having a hood like appearance, with the lower part preferably substantially longer than the upper part. These parts 1 and 2 contain the internal components of the pen and cooperate to form a complete pen casing (except for the cap, not illustrated).

The upper part 1 is formed with a cavity 3 extending upwardly from its lower end 4. The lower end 4 is formed with a shoulder 5 having a threaded outer surface 6.

The lower part 2 is formed as a hollow shell open at either end. The upper end 7 is internally threaded as illustrated at 8. The threads 8 of the lower part and the threaded outer surface 6 of the upper part are complementary and are removably interengaged to form a continuous casing having continuous outer walls. If desired a decorative ring 9 may be interposed between the parts 1 and 2.

The lower part 2 may be nonsymmetrical with an enlarged section intermediate its ends as illustrated at 11 for decorative purposes or for easier gripping, provided

2

the hollow interior through the lower part is of sufficient diameter to accommodate the internal components.

The internal components may be conventional in nature and may include an ink reservoir 13 having a rigid base 12. The base 12 is an elongated shell having a maximum outer diameter sufficient to permit it to be drawn out through the upper end of the lower part 2. The upper end of the base 12 is open and is formed with a shoulder 24 to which is secured the lower end of the resilient ink sack 15. The lower end of the base 12 is formed with an ink passage 16 connected to the interior 17 of the base 12. A recess or slot 18 is formed adjacent the passage 16 and is designed to receive and secure the upper end of the nib 19.

15 The nib 19 which is secured to the base 12 projects downwardly with its lower end or tip projecting outwardly through the lower opening 20 in the lower part 2.

The ink sack 15 projects upwardly through the lower part 2 and into the cavity 3.

20 A cylindrical sleeve 21 preferably of metal is force fit over the ink sack 15 and shoulder 24 to securely interengage the sleeve and shoulder 24. An elongated leaf spring 25 is also secured to the shoulder 24 by sleeve 21. This spring 25 is formed as an inverted U-shaped member

25 which extends over the upper end of sack 15. The bight portion 27 of spring 25 extends into the cavity 3 and is secured therein by suitable means. These means may comprise a dimple or bead 50 formed in the spring on either side thereof and projecting into a recess 51 in

30 the inner surface of upper part 1. This arrangement secures the spring against axial movement relative to the upper part, but allows the upper part to be rotated so as to engage or disengage the threaded surface 6 from threads 8. Alternate securing means which hold the internal components to the upper part while still allowing the removal of these components from the lower part may be used. Such an arrangement may comprise the structure illustrated in FIG. 4. In this arrangement the upper part 1 instead of being threaded at 6 is provided

35 with an axially engaging bayonet fit capable of engaging lower part 2 so that parts 1 and 2 can be engaged on axial movement. The bight 27 of spring 25 is secured to the top of part 1 by a rivet 60. FIG. 5 is a similar arrangement to FIG. 2 except that a plurality of inwardly extending pins 61 anchored at their outer ends in part 1 project into lateral grooves 62 in spring 25. At least three radially arranged pins are provided so that a pin always engages the grooves 62 on rotation of part 1 relative to spring 25. This effectively integrally secures the internal components to the upper part of the casing.

40 The lower part of the casing which forms a hood covering the internal components is removably interengaged with the upper part so that it may readily be detached from the internal components to expose them for filling. As used herein the term integrally secured when referring to the attachment of the upper part to the internal components is intended to refer to an interengagement or unity which will normally remain intact during use or filling of the pen, even though means may be provided for detachment for repair or other similar purposes.

What is claimed is:

1. A fountain pen comprising means forming a refillable ink reservoir, a pen nib, means forming an ink conduit and support for securing said nib at one end of said reservoir whereby ink may flow from said reservoir to said nib when said pen is in use, spring means extending from said support for filling said reservoir from an ink supply into which said nib is dipped, and a casing enclosing each of said means and substantially enclosing said nib, said casing including an upper part rotatably secured to said spring means and a lower part open at each end and enclosing the lower portions of said pen with the tip of said nib projecting outwardly therefrom, said lower part formed with an inner surface devoid of projections engaging said nib whereby said lower part may be completely removed from enclosing said lower portions.

15

2. A fountain pen as set forth in claim 1 wherein said upper and lower parts have complementary interengaging threaded portions for removably securing said parts together.

3. A fountain pen as set forth in claim 1 wherein said upper part is rotatably secured to said one of said means against axial movement with respect thereto.
